MACHINE FOR SECURING HEADS IN CYLINDRICAL CONTAINERS

Albert H. Schmidtke, St. Joseph, Mich., assignor, by mesne assignments, to Seymour & Peck Company, Chicago, Ill., a corporation of Delaware

Application April 11, 1935, Serial No. 15,784

12 Claims. (Cl. 113—16)

Cylindrical containers have been made up of a side wall of plywood having a metal strip surrounding each end adapted to surround a circular wooden head. An object of this invention is to provide a ready means for securing this head in the container.

This and other objects, as will hereinafter appear, are accomplished by this invention which is fully described in the following specification and shown in the accompanying drawings, in which:—

Figure 1 is a side elevation of a hand-operated machine embodying the invention;

Fig. 2 is a longitudinal sectional view of a shell with the first head in place but not secured therein;

Fig. 3 is the same turned end for end after the first head has been secured therein;

Fig. 4 is the same filled with both heads secured therein;

Fig. 5 is an enlarged view on the line 5—5 of Fig. 1;

Fig. 6 is an enlarged top plan view of Fig. 1;

Fig. 7 is an enlarged partial sectional view on the line 7—7 of Fig. 1 showing a support for the shell when inserting the first head;

Fig. 8 is a similar view showing a support for the shell while inserting the second head;

Figs. 9, 10, and 11 are partial side elevations of the mechanism shown in Fig. 1 showing the crimping mechanism in three positions;

Fig. 12 is a partial enlarged vertical section on the line 12 of Fig. 10;

Fig. 13 is a similar section on the line 13 of Fig. 11; and

Fig. 14 is a perspective view of a modified form of support for the shell.

Containers in the stages shown in Figs. 2, 3, and 4 each consists of a cylindrical shell 14, preferably formed from a rectangular panel of plywood, to the ends of which are fastened strip-like bands 15 of metal by means of staples or the like 16. A circular head 17 fitting snugly within the band 15 is then inserted at each end of the shell, and the present invention relates to apparatus for securing these heads in place.

The embodiment illustrated comprises a base 18 carrying a standard 19 to which a block 20 is adjustably secured by means of set screws or the like 21. In inserting the first head a support 22, shown in detail in Fig. 7, is secured to the base as by means of a screw 23. This support is of such a size as to fit rather snugly within the band 15 so that the end thrust of the shell 14 while the first head is being secured will be taken by the support 22.

In axial alignment with the shell 14 and support 22 (Fig. 1) is a plunger 24 slidably mounted in the block 20. This plunger (Fig. 12) has a foot 25 secured at its lower end as by means of a screw 26. Surrounding the foot 25 and slidably mounted on the plunger 24 is a cup-shaped member 27. This member has a series of longitudinal internal grooves 28 which are wider at the top than at the bottom so as to provide a series of splines 29 which are wider at the outside than at the inside. The foot 25 has a series of radiating fins 30, one of which lies in each of the grooves.

The interior of the cup-shaped member 27 is bored or otherwise formed to provide a cylinder 31 which, however, is interrupted by the grooves 28 and terminates at its upper end in a series of inclined faces 32, the purpose of which will later be described. The lower inner edge of the member 27 is internally chamfered at 33 to assist in placing this member over the top of the shell.

A hand-operated lever 34 is pivotally mounted at 35 on the block 20 and is operatively connected through a pin 36 and link 37 with a pin 38 on the plunger 24, this plunger being counterbalanced in all positions as by means of a spring 39 secured to an arm 40 on the block 20. The pin 38 is operative in a slot 37a in the link 37. The lever 34 also carries a pin 41 which operates in a slot 42a in a link 42, the opposite end of this link connecting through a pin 43 with an ear 27a on the cup-shaped member 27. It will be understood that there are two of the links 37 and 42, one of each on each side of the lever 34.

With the mechanism in the upper position shown in Fig. 9 a shell having the lower end still open is inserted over the support 22 and a circular head 17 is inserted. A wood member of the same length as the plywood shell and substantially filling the same is placed therein during the first crimping operation to insure against splitting the shell. The operating lever is then pulled down so as to force the cup-shaped member 27 over the top of the shell, thereby causing the inclined faces 32 to engage the top edge of the metal band 15 and to cause it to be crimped inwardly to the position 15a of Fig. 12. Initially, the cup alone will have engaged with the work, and later, as the band edge is forced inwardly, the foot also will engage therewith. When the cup is at its lowermost position, as shown in Fig. 10, the pin 38 may have traveled some distance down in the slots 37a of the pull links, as shown in Fig. 10.

As the lever 34 continues its downward move-

ment, as shown in Fig. 11, the link 37 will cause the plunger 24 to descend, as shown in Figs. 11 and 13, until the foot 25 is pressed firmly against the crimped upper portion of the metal strip-like band which now assumes the position 15^b of Fig. 13 and the crimping operation is completed, and the head 17 is firmly locked in the shell. If it is now desired to similarly lock a head in the opposite end of this shell the support 22 is removed and a new support 122 (Fig. 8) is inserted in its place, so that the top of the shell will now stand in the same relation to the crimping member that it did in the operation which has just been described.

15 The operating mechanism is both simple and effective. The arrangement of links provides, in effect, a duplex toggle mechanism which is characterized by the following action: When the operating lever starts down (see Fig. 9), a thrust is exerted through the links 42 to move the cup downwardly. The sustaining spring holds the foot up within the cup so that the foot follows along with the cup as it descends toward the work. Starting from a point where the angle is wide, the thrust links move in toward the line between the pivotal centers 35 and 43, so as to operate through a leverage which increases in power as the resistance increases. At the point of maximum leverage (see Fig. 10), both the cup and foot are exerting pressures against the work, but without any aid from the pull links 37. The movement up to this point, during which the operating lever has advanced perhaps 45°, constitutes the first stage of the operation.

35 When the lever point 41 moves past the line between the pivotal centers 35 and 43 the second stage is reached. The links 37 now exert a down pull to advance the foot against the work while the pressure exerted through the thrust links upon the cup is gradually released. The parts during this stage are in the positions shown in Figs. 11 and 13. Continuing, the pull links move in to operate through leverages of increasing power until finally the needed pressure has been applied to the work. During the last part of the movement the thrust links have allowed the lever point 41 to swing upwardly until near the end, without resistance due to the slip connection afforded by their elongated slots. Near the end of this movement a pull is exerted upon the thrust links whereby the cup is lifted slightly, as indicated in Fig. 13, thereby tending to free the cup for subsequent disengagement from the work. On the return stroke of the operating lever, the spring exerts a counterforce sufficient to balance partially or completely the weight of the parts which require lifting to their initial positions.

It will be observed that the action just described is peculiar in that there are two stages of movement each characterized by the working links exerting at the start a minimum leverage which increases as the movement proceeds; that there is little or no resistance on the part of the non-working links and associated parts while the other set of links are doing their work; that in these sequential stages of movement there is utilized a single operating lever whose movement range is conveniently small—perhaps only 90°; that the rate of advance of the cup in this first stage is perhaps twice as fast as that of the foot in the second stage, due to the difference in the radii of the points 41 and 36; that the thrust links are active only in the first stage, and at the conclusion of the second stage, of movement, whereas it is only in the second stage that the pull links

do any work; and that the cup which is fitted tightly around the work is moved away therefrom at the conclusion of the down stroke of the operating lever, so as to facilitate ready disengagement of the cup from the work on the upstroke 5 of the lever.

When the shell is filled with a light material the support 122 may be used, whereas when the shell is filled with a heavy material, like steel rods, too much effort is expended lifting the shells 10 on and off the support. Consequently, a flat base 18^a (Fig. 14) is provided with a guide 18^b which is adjustably secured thereon by bolts 18^c so as to position the cylindrical shell in proper alignment. In order to use this base, adjustment of the block 15 20 is required because of the difference in height from the support 22.

I claim:

1. Means for crimping a metal band of substantially uniform height about a circular head, 20 said means comprising a support for a shell having such a band to be crimped, a standard associated with the support, a lever pivotally carried by the standard, a member operably connected to the lever and adapted to surround the 25 outer edge of the metal band and having a series of surfaces separated by V-shaped grooves and inclined inwardly at substantially 45° and adapted to engage the outer edge of the metal band at intervals therealong so as to crimp the metal band 30 and bend it inwardly, and a second member having outwardly extending V-shaped fins operable in the grooves and said member being operably connected to the lever for pressing the crimped and inwardly bent edge of the metal band down 35 against the head.

2. Means for crimping a metal band of substantially uniform height about a circular head, 40 said means comprising a support for a shell having such a band to be crimped, means for crimping the outer edge of the metal band and bending it inwardly and downwardly into a position substantially 45° from the head, other means operable thereafter for pressing this crimped edge down substantially flat and into contact with the 45 head, and means for retracting the first mentioned means while the second mentioned means is pressing the crimped edge against the head.

3. In means for crimping a metal band about a circular head, a support for a shell having such 50 a band to be crimped, means for crimping the outer edge of the metal band and bending it inwardly and downwardly into a position substantially 45° from the head, and means for pressing this crimped edge down substantially 55 flat and into contact with the head, the first mentioned means being cup-shaped and adapted to slide over the metal band and having internal longitudinal ribs which engage the metal band at intervals, and the second mentioned 60 means being slidable within the first mentioned member and having ribs interdigitating with the ribs of the first mentioned means and movable relative thereto to bear upon the angularly bent and crimped portion of said band.

4. In means for crimping a metal band about a circular head, a support for a shell having such a band to be crimped, means for crimping the outer edge of the metal band inwardly and downwardly into a position substantially 45° 70 from the head, and means for pressing this crimped edge down substantially flat and into contact with the head, the first mentioned means being cup-shaped and adapted to slide over the metal band and having internal longitudinal V- 75

shaped ribs, and the second mentioned means being slidable within the first mentioned means and having V-shaped grooves within which said ribs are slidable, the lower part of the ribs in the cup-shaped means being cut away to admit the metal band in the cup-shaped means.

5. In means for crimping a metal band about a circular head, a support for a shell having such a band to be crimped, means for crimping the outer edge of the metal band and bending it inwardly and downwardly into a position substantially 45° from the head, and means for pressing this crimped edge down substantially flat and into contact with the head, the first 10 mentioned means being cup-shaped and adapted to slide over the metal band and having V-shaped internal longitudinal ribs, and the second mentioned means being slidable within the first mentioned means and having V-shaped 15 grooves within which said ribs are slidable, the lower part of the ribs in the cup-shaped means being cut away to admit the metal band in the cup-shaped means, and said ribs terminating at the cut away portion in inwardly and upwardly 20 inclined surfaces.

6. In means for crimping a metal band about a circular head, a base having a support for a cylindrical shell having such a band to be crimped, an upright carried by the base, a plunger slidably mounted in the upright on the axis of the shell, a foot on the plunger, a cup-shaped member slidable on the plunger having a series of spaced inclined surfaces, a lever fulcrumed on the upright, a linkage operably connecting the lever to the cup-shaped member, a linkage operably connecting the lever to the plunger, the first linkage operating in advance of the second linkage whereby movement of the lever will cause the cup-shaped member to crimp 30 the metal band and bend it inwardly and further movement of the lever will cause the foot to press the crimped edge against the head, and means for counterbalancing the lever and parts movable thereby in various adjusted positions.

45. 7. In means for crimping a metal band about a circular head, a support for a shell having such a band to be crimped, a standard associated with the support, a lever pivotally carried by the standard, a first member operably connected to the lever for crimping and bending the metal band inwardly, and a second member operably connected to the lever for pressing the inwardly crimped edges of the metal band down against the head, the first member being operably connected to the lever through a pair of thrust links while the second member is operably connected to the lever through a pair of pull links.

8. In means for crimping a metal band about a circular head, a support for a shell having such a band to be crimped, a standard associated with the support, a lever pivotally carried by the standard, a first member operably connected to the lever for crimping the metal band inwardly, and a second member operably connected to the lever for pressing the inwardly crimped edges of the metal band down against the head, the first member being operably connected to the lever through a pair of thrust links while the second member is operably connected to the lever

through a pair of pull links, the second member continuing the crimping operation after the first member has completed its crimping operation and is being withdrawn.

9. In means for crimping a metal band about a circular head, a support for a shell having such a band to be crimped, a standard associated with the support, a lever pivotally carried by the standard, a first member operably connected to the lever for crimping the metal band inwardly, and a second member operably connected to the lever for pressing the inwardly crimped edges of the metal band down against the head, the first member being operably connected to the lever through a pair of thrust links while the second member is operably connected to the lever through a pair of pull links, the second member continuing the crimping operation after the first member has completed its crimping operation and is being withdrawn, the second member lying within the first.

10. In means for crimping a metal band about a circular head, a support for a shell having such a band to be crimped, a standard associated with the support, a lever pivotally carried by the standard, a member operably connected to the lever and adapted to surround the outer edge of the metal band and having a series of distinct, circumferentially spaced separated surfaces extending inwardly and adapted to engage the outer edge of the metal band at intervals therealong so as to crimp the metal band and bend it inwardly, and a second member operably connected to the lever for pressing the inwardly crimped edges of the metal band down against the head.

11. In means for crimping a metal band about a circular head, a support for a shell having such a band to be crimped, a standard associated with the support, a lever pivotally carried by the standard, a member operably connected to the lever and adapted to surround the outer edge of the metal band and having a series of distinct, circumferentially spaced and beveled crimping elements adapted to engage the outer edge of the metal band at intervals therealong so as to crimp the metal band and bend it inwardly, and a second member having spaced fins extending between the crimping elements, said second member being operably connected to the lever for pressing the inwardly bent and crimped edge of the metal band down against the head.

12. In means for crimping a metal band about a circular head, a support for a shell having such a band to be crimped, a standard associated with the support, a lever pivotally carried by the standard, a member operably connected to the lever and adapted to surround the outer edge of the metal band and having a circular series of spaced tooth-like crimping elements adapted to engage the outer edge of the metal band at intervals therealong so as to crimp the metal band and bend it inwardly, and a second member having spaced fins extending between the crimping elements, said second member being operably connected to the lever for pressing the inwardly crimped edges of the metal band down against the head.

ALBERT H. SCHMIDTKE.
